O. CLANCY

LOG RAFT

Filed July 20, 1923

INVENTOR.

Oscar Clancy
By James J. Taylor, A.T.T.Y.

UNITED STATES PATENT OFFICE.

OSCAR CLANCY, OF QUEEN CHARLOTTE ISLANDS, BRITISH COLUMBIA, CANADA.

LOG RAFT.

Application filed July 20, 1923. Serial No. 652,792.

To all whom it may concern:

Be it known that I, OSCAR CLANCY, a subject of the King of Great Britain, and a resident of Queen Charlotte Islands, in the Province of British Columbia, Canada, have invented certain new and useful Improvements in Log Rafts, of which the following is a specification.

My invention relates to improvements in log rafts, and the object of my invention is to devise a means of transporting logs from place to place in raft-form in which the logs are strongly and securely bound together whereby the raft so formed is not liable to be broken up in rough weather, the arrangement being such that the logs forming the raft may be spilled easily from either side of the raft centre on reaching the unloading ground so that a great saving in both time and labour is rendered possible and at the same time minimizing the risk of a log jam when spilling. A further object is to so arrange the "bottom-top" cables, that is, the lines passing over the upper body of the raft, in such manner that they are readily accessible so that they can be unloosed and taken off at any time and, if required, before spilling the raft.

I attain these objects by the construction illustrated in the accompanying drawings in which—

Fig. 1 is a cross sectional view of the raft floor, taken in front of a cable.

Fig. 2 is a diagrammatic view of one floor cable winding.

Fig. 3 is a diagrammatic view of another floor cable winding.

Fig. 4 is a cross sectional view of the raft floor showing the "bottom-top" cable arrangement.

Fig. 5 is a fragmentary view illustrating a pair of cables in position.

Fig. 6 is a cross sectional view of a loaded raft.

Similar figures of reference indicate similar parts throughout the several views.

In constructing a raft according to my invention a main central log 1 is laid down, from which log the whole fabric depends. In long rafts of course this centre log is formed out of a number of logs placed end to end and chained together in the well known manner. On each side of the centre log 1 are placed side by side the logs which

form the raft floor, these being indicated by the numeral 2, and being in number as many as are required to make up the width and length of the raft, and along each side of the outermost floor logs 2 are placed the "side sticks" 4 and 5, these side sticks being as many in number laid end to end and chained together in the usual manner as are required to extend the entire length of the raft. These logs above-mentioned constitute the floor of the raft and they are bound together by spaced pairs of cables arranged throughout the length of the floor and indicated by the numerals 6—7 on one side of the centre log 1 and 8—9 on the opposite side. The cables are wrapped around the floor logs in the manner shown in Fig. 5 with reference to cables 6 and 7 and diagrammatically in Figs. 2 and 3, that is to say, the cable 6 is secured to the centre log 1 at 75 one end in any suitable manner such as by taking a turn round the centre log and then clamping the end thereto, as indicated at 10, after which it is then passed over the top of the floor log 2 next the centre log 80 and under and around it, then carried over the top of it and on to the next floor log, passing over the top of it and then under and around it and so on until it has been wrapped around all the floor logs on that 85 side of the centre log, being finally passed around the side stick 4 one turn and having its free end clamped to it, as at 11. The cable 8 on the opposite side of the centre log is wrapped around the logs on that side 90 in the same manner and secured to the side stick 5 by the clamp 12.

The cable 7 of the pair 6—7 is spaced a short distance from the cable 6, say about 4 feet apart, and it is also secured at one end to the centre log 1 by the clamp 13 and then wound around the floor logs on the same side as the cable 6 in a similar manner to the winding of that cable, only the cable 7 is passed all the time first under the bottom of 100 the logs and then around them, being finally clamped at its free end, as at 14, to the side stick 4. The cable 9 of the pair 8—9 on the opposite side of the centre log is wrapped around the logs in the same manner as has 105 just been described with reference to cable 7 and its free end is also clamped to side stick 5.

It will thus be seen that the floor of the raft consists of a main central log extending 110

longitudinally of the raft on each side of which is laid a floor of longitudinally extending logs, each such floor being bounded on the outside by longitudinal side sticks 5 connected end to end and that the logs of the floor so constructed on each side of the centre log are firmly bound together by cables arranged at designated points throughout the length of the raft in spaced pairs, the cables 10 of each pair being secured at one end to the centre log and being then wrapped around the logs of the respective floor, one cable passing all the time first over the top of the logs and the other cable passing all the time 15 first under the bottom of the logs, or in other words, the cables of a pair, starting from the centre log, are wound around their respective logs oppositely to each other, as indicated in Figs. 2, 3 and 5, their free ends being 20 finally secured to the side sticks so that the logs are prevented from rolling and the whole floor is firmly bound together.

Thus is formed the floor of the raft on which the main body of loose logs, indicated 25 by the numeral 16, is loaded, and these logs 16 are securely held together on the floor by means of the "bottom-top" cables 17 and 18, which cables are arranged as shown in Fig. 4, that is, the cable 17 is passed at one end 30 around the side stick 4 and clamped to it, its free end being then passed downwardly between the side stick and the adjacent floor log, and then carried along transversely under the floor of the raft and passed upwardly 35 between the side stick 5 and the adjacent floor log 2 so that its free end hangs over the side stick 5 when the raft is being loaded. The cable 18 is arranged in a similar manner, being clamped at one end around the 40 side stick 5, its free end passing downwardly between the side stick and the adjacent floor log and being then carried transversely under the raft floor and passed upwardly between the side stick 4 and the adjacent floor 45 log, hanging at its free end over the side stick 4 when loading. After the raft is constructed and loaded to the full capacity the free ends of the "bottom-top" cables 17 and 18 are then gathered up and brought together 50 and clamped tightly on top of the main body of the logs 16, as shown in Fig. 6.

The ends of the raft are formed in any approved manner and need not be described.

The utility and advantages of such a raft 55 will be readily apparent, as it will be seen that the logs may be spilled readily from both sides of the centre so that a log jam when discharging is not liable to occur and as the floor is in effect formed of two independent side floors the cables connecting the 60 logs of each floor are reduced to a minimum length so that they are handled and manipulated with comparative ease, while a further advantage lies in the arrangement of the 65 "bottom-top" cables which, it will be seen,

are readily accessible and may be taken off at any time and, if required, without the necessity of spilling the raft.

It will be evident, therefore, that I have devised a log raft which is capable of being 70 constructed and operated with great facility, thus providing a useful and convenient means for transporting large bodies of logs from place to place.

What I claim as my invention is:—

1. In a log raft, a floor comprising a centre log and logs arranged side by side on each side of it, and means secured to said centre log flexibly connecting the side logs to it and to each other whereby independent side floors are formed on opposite sides of the centre log adapted to support a load of logs and the freeing of the outer end connections of each of which floors tends to disintegrate the raft including the 85 floors in opposite directions outwardly while the inner end connections remain connected to the centre log.

2. In a log raft, a floor comprising a centre log, logs arranged side by side on each side of said centre log, cables for each set of side logs each of which is secured at one end respectively to the centre log and is wrapped around each log in the set and secured at its free end to the outermost 90 log whereby independent side floors are formed on opposite sides of the centre log adapted to support a load of logs and the freeing of the outer end connections of each of which floors tends to spill the log-loads 95 in opposite directions outwardly.

3. In a log raft, a floor comprising a centre log, logs arranged side by side on each side of said centre log, cables for each set of side logs arranged in pairs, the cables of each respective pair being secured at one end to the centre log and wrapped around each log in the set and secured at their free ends to the outermost log, one cable passing first over the top of each log and then 105 around it while the other cable passes first under each log and then around it whereby independent side floors are formed on opposite sides of the centre log adapted to support a load of logs and the freeing of the 110 outer end connections of each of which floors tends to spill the log-loads in opposite directions outwardly.

4. In a log raft, a floor comprising a centre log, logs arranged side by side on each side of said centre log, cables for each set of side logs each of which is secured at one end to the centre log and is wrapped around each log in the set and secured at its free end to the outermost log, and means 120 for securing a load of logs on said floor, said means comprising cables on each side of the load each secured at one end to the respective outermost logs on the opposite 125 sides of the raft, their free ends being passed 130

first downwardly between the said outermost logs and their adjacent floor logs, then carried transversely under the floor and passed upwardly between the respective opposite side outermost logs and their adjacent floor logs, being finally brought together and secured on top of the load.

5. In a log raft, a floor comprising a centre log, logs arranged side by side on each side of said centre log, cables for each set of side logs arranged in pairs, the cables of each respective pair being secured at one end to the centre log and wrapped around each log in the set and secured at their free ends to the outermost log, one cable passing first over the top of each log and then around it while the other cable passes first under each log and then around it, and means for securing a load of logs on said floor, said means comprising cables on each side of the load each secured at one end to the respective outermost logs on the opposite sides of the raft, their free

ends being passed first downwardly between the said outermost logs and their adjacent floor logs, then carried transversely under the floor and passed upwardly between the respective opposite side outermost logs and their adjacent floor logs, being finally brought together and secured on top of the load.

6. In a log raft, the combination with a floor of logs, of means for securing a load of logs on said floor, said means comprising cables on each side of the load each secured at one end to the respective outermost logs on the opposite sides of the raft their free ends being passed first downwardly between the said outermost logs and their adjacent floor logs, then carried transversely under the floor and passed upwardly between the respective opposite side outermost logs and their adjacent floor logs.

Dated at Thurston Harbor, B. C., this 19th day of June, 1923.

OSCAR CLANCY.
